UNITED STATES PATENT OFFICE.

CHARLES F. BOYCE, OF STERLING BUSH, NEW YORK.

FOLDING BOX.

SPECIFICATION forming part of Letters Patent No. 437,769, dated October 7, 1890.

Application filed July 23, 1890. Serial No. 359,669. (No model.)

To all whom it may concern:

Be it known that I, CHARLES F. BOYCE, a citizen of the United States, residing at Sterling Bush, in the county of Lewis and State 5 of New York, have invented certain new and useful Improvements in Folding Boxes; and I do declare the following to be a full, clear, and exact description of the invention, such as will enable others skilled in the art to 10 which it appertains to make and use the same, reference being had to the accompanying drawings, and to the letters of reference marked thereon, which form a part of this specification.

15 This invention relates to certain new and useful improvements in folding boxes; and it relates more particularly to the construction of that class of boxes which are adapted for use in packing goods or merchandise for transportation.

20 The invention has for its object to provide a box of the character mentioned, which may be cheaply constructed, and which will be strong and durable and will effectually protect its contents against possible injury in transit, and which at the end of the route may be compactly folded and returned to the shipping-point.

25 To the above ends and to such others as 30 the invention may pertain the same consists in the peculiar construction and in the novel combination, arrangement, and adaptation of parts, all as more fully hereinafter described, shown in the accompanying drawings, and 35 then particularly defined in the appended claim.

The invention is clearly illustrated in the accompanying drawings, which, with the letters of reference marked thereon, form a part 40 of this specification, like letters of reference indicating like parts throughout the several views, and in which drawings—

45 Figure 1 is a perspective view of the box as it appears when in actual use. Fig. 2 is a like view of the box as it appears when folded for storage or for reshipping. Figs. 3 and 4 are perspective details of the hinges and jointed hook detached.

50 Reference now being had to the details of the drawings by letter, A designates the box, which may be of any desired size of form, but

which in the present instance I have shown as rectangular and consisting of the top B, bottom C, front and rear sides D and E, and ends F. The front and rear sides of the box 55 are connected with the ends F by the hinges a and a', the hinges a being placed at diagonally-opposite corners of the box upon the inside of the box, while the hinges a' at the remaining corners of the box are secured 60 upon the outer faces of the side and end sections, as shown. It will be seen that by this construction when the top and bottom of the box are open the body portion of the box may be readily folded or collapsed. 65

The box is provided at its ends with heavy protecting-strips G, which when the box is complete and the cover or top closed form continuous bands extending entirely around the box, the overlapping ends of the strips at 70 the corners of the box being beveled to form miter-joints, as shown at c.

The top B is hinged to the upper ends of the strip G upon the rear face of the box by means of the heavy strap-hinges H, the knuckles 75 of which hinges are sufficiently heavy to form substantial bumpers, which serve to protect the corners of the box from possible injury.

When closed, the cover B is secured in place by means of the jointed hooks I, said hooks 80 being constructed of heavy material and consisting of the body portion I' and hook proper I''. The portion I' of the hook is secured to the upper face of the strip G upon the cover at a point adjacent to the end of the strip by 85 means of a staple i, provided for the purpose, while the hook portion I'' is adapted to engage a similar staple i' upon the outer face of the strip G upon the face of the box. Both the joint i' of the hook I and also the knuckle of 90 the hinge H are of sufficient size to form an effectual protection to the corners of the box.

As a further protection to the ends of the box I provide the ends with heavy strips G'', which strips are securely bolted or otherwise 95 secured to the outer face of the end sections adjacent to their outer edges.

When the box is folded for transportation, the hooks I are adapted to engage the staples k, and thus serve to hold the parts against accidental displacement during transit. 100

Having thus described my invention, what

I claim to be new, and desire to secure by Letters Patent, is—

The combination, with the folding box provided with protecting-strips G surrounding the same and having miter-joints, of the hinges and locking or securing hooks, having enlarged knuckles arranged upon said strips at the angles of the box and adapted to serve

as bumpers for protecting the angles of the box, substantially as described.

In testimony whereof I affix my signature in presence of two witnesses.

CHARLES F. BOYCE.
